(57) **CLAIM**

The ornamental design for a autonomous vehicle as shown and described.

DESCRIPTION

FIG. 1 is a perspective view of the autonomous vehicle of the present design;

FIG. 2 is a front view of the autonomous vehicle of FIG. 1; FIG. 3 is a back view of the autonomous vehicle of FIG. 1; FIG. 4 is a left side view of the autonomous vehicle of FIG. 1;

FIG. 5 is a right side view of the autonomous vehicle of FIG. 1;

FIG. 6 is a top view of the autonomous vehicle of FIG. 1; and,

FIG. 7 is a bottom view of the autonomous vehicle of FIG. 1.
